UNITED STATES PATENT OFFICE.

HARRY S. BERGEN, OF TOLEDO, OHIO.

WORKHOLDING DEVICE.

Application filed September 26, 1921. Serial No. 503,198.

To all whom it may concern:

Be it known that I, HARRY S. BERGEN, a citizen of the United States, residing at Toledo, in the county of Lucas and State of Ohio, have invented certain new and useful Improvements in Workholding Devices, of which the following is a specification.

This invention relates to work holding devices, and particularly to means for holding 10 castings in position while they are being machined.

One of the objects of the invention is to provide an improved device by means of which castings may be held in position by 15 a plurality of clamps, the pressure of each of the clamps being substantially the same regardless of variations in the thickness of the parts of the casting engaged by the clamps.

20 Another object of the invention is to provide a work holding device having a plurality of casting engaging clamps which may be simultaneously moved to clamping position by the operation of a hand wheel.

25 Another object is to provide a work holding device having an improved locating means which will properly position castings.

Still another object is to provide a device in which the clamping and locating 30 means may be brought into operative engagement with the part to be machined by a quick and easy operation and in which rapid disengagement thereof is also permitted, thus saving a large part of the time now lost in 35 removing the finished parts and positioning new parts in the fixture.

Other objects and advantages will be apparent from the following description, in which reference is had to the accompanying drawings 40 illustrating a preferred embodiment of my invention and wherein similar reference numerals designate similar parts throughout the several views.

In the drawings:—

45 Figure 1 is a plan view of a work holding device embodying my invention, a substantially annular scale housing casting being shown as fixed in position thereon;

50 Figure 2 is an enlarged elevational view of the work holding device with a casting fixed in position thereon, parts of the device and the casting being shown in section.

55 Figure 3 is a vertical sectional view on a reduced scale showing a part of a device for locating a casting to be machined.

Although I have shown the device as

adapted for use in machining a casting for a scale housing, it is to be understood that it has been so shown for purposes of illustration only and that it is also adapted for 60 use with castings of other shapes, as such changes in the form and location of the various parts of my device as are necessary to fit it with castings of other shapes may be readily made by one skilled in the 65 art.

Referring to the drawings in detail, the base 1 of the work holding device is provided with suitable notches or slots 2 to facilitate its attachment to a metal working machine. Projecting upwardly from the base are three substantially equidistant work supporting members 3 upon which the casting C to be machined is positioned. The casting C is centrally located upon the 70 fixture by means of the diametrically oppositely disposed lugs 4 and 5, the lug 4 having a rounded outer end adapted to be received in a notch in the casting, and the lug 5 having a notch adapted to receive 75 a protuberance on the casting.

The lugs 4 and 5 are mounted respectively upon radially movable members 6 and 7 located in grooved cover plates or guides 8 and 9 which are secured to the base 1. The inner ends of the members 6 and 7 contact with the opposed faces of a wedging block 10, said block having substantially the shape of the frustum of a pyramid. The block 10 is integral with a vertically disposed 80 shaft 11 that extends upwardly through a loosely fitted tube 12 which has a lower flange 13 resting upon the base 1. The upper portion of the shaft 11 is threaded, as at 14, to receive a star wheel 15 which is 85 adapted to rest upon the upper end of the tube 12.

By turning the star wheel 15 so as to draw the shaft 11 and the block 10 upwardly, the tapered faces of the block are caused to exert 100 wedging pressure upon the ends of the members 6 and 7 (see Figure 1) to force them outwardly, thus moving the lugs 4 and 5 respectively into engagement with a notch 16 and a boss 17 upon the casting C and thereby locating the casting upon the fixture. The members 6 and 7 are slidable in the grooved cover plates 8 and 9. When the star wheel 15 is rotated in the opposite direction the shaft 11 and wedging block 10 are permitted to move downwardly, thus relieving 105 the horizontal pressure on the members 6 110 and 7.

and 7, which are then withdrawn from contact with the casting by the retractile springs 32, the inner ends of which are pinned or otherwise fastened to the cover plates 8 and 5 9, while their outer extremities are fastened to the slidable members 6 and 7.

The casting C is held in rigid position upon the work holding fixture by means of a plurality of clamping bars or jaws 18 preferably located so as to engage the casting in juxtaposition to the supporting members 3 so that the liability of springing or warping of the casting will be reduced to a minimum. The clamping bars 18 are mounted upon 15 pins 19 which are positioned in bosses 20, said bosses preferably being cast integral with the base 1, the bars 18 being provided with longitudinally extending slots 21 so that they may be moved radially out of the 20 way of the casting while it is being placed upon or removed from the fixture. The inner ends of the bars 18 rest upon the upper surface of a disk 22 which is loosely mounted upon the flange 23 projecting from a vertically disposed sleeve 24, the engaging surfaces of the flange and disk being spherical so that the disk is universally mounted upon the flange and is therefore free to wabble except as it is restrained by the pressure 25 of the inner ends of the bars 18.

The upper portion of the sleeve 24 is threaded to receive an internally threaded bushing 25 which is fixed within an annulus depending from a hand wheel 26 which is journaled upon the reduced upper end of the tube 12 and is held in place by means of a shoulder 27 on the tube and a pair of lock nuts 28 and 29. A stud 30 projecting inwardly from the sleeve 24 into a vertical groove 31 in the tube 12 prevents rotation of the sleeve on the tube but permits the sleeve to move vertically thereon.

From the foregoing description it is believed to be apparent that by rotating the hand wheel 26 in a direction to draw the sleeve 24 upwardly the disk 22 is also moved upwardly, thus exerting an upwardly acting force upon the bars 18, the opposite ends of which are thereby forced downwardly upon the casting C so that the casting is rigidly held in place on the fixture. Since the disk 22 is universally connected to the sleeve 24 the clamping pressure is equalized among the bars 18 and the casting is tightly clamped against each of the work supporting members 3 regardless of slight variations in the thickness of the casting.

While it will be apparent that the illustrated embodiment of my invention herein disclosed is well calculated to adequately fulfill the objects primarily stated, it is to be understood that the invention is susceptible to variation, modification and change within the spirit and scope of the subjoined claims.

Having described my invention, I claim:

1. In a device of the class described, in combination, a universally mounted member, a plurality of clamping members engageable therewith, and means for moving said universally mounted member whereby equalized force is simultaneously exerted upon each of said clamping members. 70

2. In a device of the class described, in combination, a rectilinearly movable member, an equalizing member universally mounted thereon, and a plurality of clamping members engageable with said equalizing member. 75

3. In a device of the class described, in combination, a base, a plurality of work supporting members, a plurality of clamping members, and means for simultaneously exerting equalized pressure upon said clamping members, said means comprising a rectilinearly movable member, a member universally mounted thereon and adapted to engage said clamping members, and means for moving said rectilinearly movable member in both directions. 80 85 90

4. In a device of the class described, in combination, a base, a plurality of work supporting members, a plurality of clamping members, means for simultaneously exerting equalized pressure upon said clamping members, and means for locating a part to be machined upon said supporting members, said means comprising a plurality of radially disposed thrust members, and means for moving said thrust members outwardly with equalized pressure. 95 100

5. In a device of the class described, in combination, a base, a plurality of work supporting members, a plurality of clamping members, means for simultaneously exerting equalized pressure upon said clamping members, said means comprising a sleeve, a disk-like member universally mounted thereon and engageable with said clamping members, and means to move said sleeve endwise. 105 110

6. In a device of the class described, in combination, a base, a plurality of clamping bars pivotally mounted on said base, said bars being movable endwise when relieved from clamping force, and means for simultaneously exerting equalized clamping force on said bars. 115

7. In a device of the class described, in combination, a base, a plurality of clamping bars pivotally mounted on said base, said bars being movable endwise when relieved from clamping force, and means for simultaneously exerting equalized clamping force on said bars, said means comprising a universally mounted member engageable with said bars, and means for moving said universally mounted member whereby it is caused to exert pressure on said bars. 120 125 130

8. In a device of the class described, in

combination, a base, work locating means on said base, said work locating means comprising a plurality of thrust members, guides for said thrust members, a wedging device, means for forcing said wedging device into wedging engagement with the ends of said thrust members and thereby forcing said thrust members into engagement with a part to be worked, and resilient means for withdrawing said thrust members from engagement with such part.

9. In a device of the class described, in combination, a base, work locating means on said base, said work locating means comprising a plurality of thrust members, guides for said thrust members, a tapered block, a shaft secured thereto, means for imparting endwise movement to said shaft and thereby forcing said block into wedging engagement with said thrust members, whereby said thrust members are forced into engagement with a part to be worked, and resilient means for withdrawing said thrust members from engagement with such part.

10. In a device of the class described, in combination, a base, work locating means on said base, said work locating means

comprising a plurality of thrust members, guides for said thrust members, a wedging device, means for forcing said wedging device into wedging engagement with the ends of said thrust members and thereby forcing said thrust members into engagement with a part to be worked, resilient means for withdrawing said thrust members from engagement with such part, a plurality of work supporting members, a plurality of clamping members, and means for simultaneously exerting equalized pressure upon said clamping members.

11. In a device of the class described, in combination, a base, a plurality of clamping bars, each of said clamping bars having a pin-and-slot connection with said base, a universally mounted member engaging the ends of said clamping bars, and means for moving said universally mounted member and thereby simultaneously exerting an equalized force in the same direction upon each of said clamping bars.
